END GATE AND LATCHING STRUCTURE
Leonard J. Reimer, Danbury, Iowa
Filed May 18, 1960, Ser. No. 29,835
5 Claims. (Cl. 295—51)

My invention relates to an end gate and a latching structure for the same.

An object of my invention is to provide an end gate having a unique combination of latching structures whereby said end gate can be pivoted from the top or the bottom, and which latching structures will provide means for insuring that none of the latches will become disengaged while the other latches are being manipulated, and to further provide means whereby the entire end gate can be removed when desired.

A further object of my invention is to provide a latching structure which will maintain the uniform spacing of the wagon sides and to thereby prevent changes due to warpage.

A further object of my invention is to provide means which besides providing locking means for the latches will be at the same time provide means for holding the end gate at desired supported elevation or angle.

With these and other objects in view, my invention consists in the construction, arrangement, and combination of the various parts of my device, whereby the objects contemplated are attained, as hereinafter more fully set forth, pointed out in my claims, and illustrated in the accompanying drawings, in which:

FIGURE 1 is a rear view of my end gate as attached to a wagon box employing my latching structure,

FIGURE 2 is an enlarged detail of one of the upper latching structures,

FIGURE 3 is a sectional view taken along the lines 3—3 of FIGURE 2,

FIGURE 4 is an enlarged sectional detail taken along the lines 4—4 of FIGURE 1,

FIGURE 5 is an enlarged sectional detail taken along the lines 5—5 of FIGURE 1, and

FIGURE 6 is a side elevation of the end gate in a supported position.

My invention contemplates the provision of an end gate having a variety of features which will allow for convenient removal of the end gate, or which will allow for pivoting of the same at either the top or the bottom.

I have used the character 10 to designate a rear wall of a wagon box, which wall in itself provides the end gate, the character 11 indicating a pair of vertical members having the channel portions 12 adapted to slidably receive the side edges of an upwardly movable auxiliary gate 13 to which gate are attached the pieces 14 to which are pivotally attached at 15 the links 16 which engage at 17 the handle 18 which is pivoted as at 19 within the angle-shaped members 20 which are suitably secured to the members 11.

Attached to the end gate 10 are the vertical side strips 21, and attached to the members 21 are the straps 22 which extend into the outwardly bent portions 23 which extend into the further portions 24 which are attached to the bearings 25, similar members 22, 23, 24, and 25 also being attached to the vertical members 11.

Received within the bearings 25 and rotatable therein are the pair of shafts 26 to which are attached the U-shaped handles 27, and receiving the shafts 26 are the torsion springs 28 which springs are suitably attached as at 29 (see FIGURE 5) to the bracket portions 30, which portions 30 extend into the side flanges 31. The ends of the torsion springs 28 are secured as at 32 to the shafts 26.

The side flanges 31 include the substantially circular

2

openings 33 (see FIGURE 4) and passing within the openings 33 are the substantially rectangular or flattened ends 34 of the shafts 26. The openings 33 extend into the reduced width portions 35, the passages 35 being slightly larger than the thickness of the portions 34.

Attached to the upper ends of the vertical strips 21 are the flanges 36 which terminate in the bearings 37 through which bearings pass the further short shafts 38 (see FIGURE 2), which shafts 38 extend into the flattened substantially rectangular portions 39, and attached to the ends of the portions 39 are the latch bars 40, and attached to the latch bars 40 are the ears 41 to which are attached at 42 the chains 43, these chains hanging downwardly and thence extending upwardly as shown in FIGURE 1, with certain of the links of these chains passing through the slots 44, which extend into the larger circular openings 45 to allow passage of the chains therethrough, the openings 45 being provided in the flanges 46, which are provided as a part of the wagon box, and being suitably attached to the base 47 of the wagon box, the flanges 46 extending into the flanged portions 48 at right angles thereto, and attached to the flanged portions 48 are the upper plates 49 which include the substantially circular openings 50 which openings 50 are adapted to receive the flattened portions 39, the openings 50 extending into the reduced passages 51 which are slightly larger than the thickness of the portions 39. Attached at the inner ends of the shafts 38 are the cotter key and washer arrangements 52.

30 The arrangement is operated in the following manner. If it is desired to discharge grain from the unit, the handle 18 is swung upwardly on the pivoting points 19 which will cause the links 16 to draw the auxiliary gate 13 upwardly, a suitable opening being provided behind the gate 13.

35 The torsion springs 28 are adjusted or set so that normally the flattened portions 34 of the shafts 26 will be in the position shown in FIGURE 4, or in the locked position.

40 However, when it is desired to swing the lower end of the end gate outwardly for any desired reason (see FIGURE 6), the handles 27 are first swung in the direction of the arrow shown in FIGURE 4 whereby the flattened portions 34 will be allowed to pass through the passages 35, and whereby the lower end of the end gate 45 can then be swung outwardly and being pivoted on the short shafts 38.

45 During this action it is essential that the upper corner arrangements comprising the flattened portions 39 etc. do not move out of place, and this is accomplished by means of the relatively heavy chains 43 which due to their weight will maintain the flattened portions 39 in their locked position, or in other words, in position so that they cannot rotate and thereby escape through the passages 51. As a result the lower end of the end gate 55 can be swung outwardly without the entire end gate becoming detached.

50 When it is desired to release the upper corners of the end gate, the latch bars 40 are merely moved to 90° from the positions shown in FIGURES 1 and 2 whereby the flattened portions 39 will be allowed to pass through the passageways 51, and at the same time the torsion springs 28 will maintain the flattened portions 34 in locked position so that the lower portions cannot escape from the flanges 31.

55 As a result of the above described arrangement, either the top or the bottom of the end gate can be swung outwardly at will.

60 After pivoting the end gate from the lower portions as shown in FIGURE 6, the chains 43 which are locked at 44 will support the gate 10 in any angle desired and as shown.

The washer arrangements 52 as well as the latches 40 also serve to prevent any spreading action of the side walls of the wagon box since the plates 49 by being positioned between these portions will prevent warpage and the like.

When it is desired to remove the entire end gate from the wagon box, the latches 40 are first rotated and the upper corners will then be released as above described, and then the handles 27 are swung to release the lower corners as described.

It will now be seen that I have provided the advantages mentioned in the objects of my invention with further advantages being apparent.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. In combination with a wagon box, an end gate including latching structures at the upper corners thereof, and at the lower corners thereof, retaining members attached to said wagon box adapted to cooperate with said latching structures, means for locking said upper latching structures against displacement while releasing said lower latching structures, and means for locking said lower latching structures against displacement when releasing said upper latching structures, said latching structures including flanges attached to said wagon box having arcuate openings therein, upper and lower bearings attached to said end gate including upper shafts journalled in said upper bearings, said openings having slot portions, said upper shafts including flattened end portions adapted to pass through said slot portions when said upper latching structures are to be released, means for retaining said upper latching structures in said locked position including latch bars attached to said upper shafts, chains attached to said latch bars, the weight of said chains providing means for maintaining said flattened portions substantially at right angles to said slot portions.

2. In combination with a wagon box, an end gate including latching structures at the upper corners thereof, and at the lower corners thereof, retaining members attached to said wagon box adapted to cooperate with said latching structures, means for locking said upper latching structures against displacement while releasing said lower latching structures, and means for locking said lower latching structures against displacement when releasing said upper latching structures, said latching structures including flanges attached to said wagon box having arcuate openings therein, upper and lower bearings attached to said end gate including upper shafts journalled in said upper bearings, said openings having slot portions, said upper shafts including flattened end portions adapted to pass through said slot portions when said upper latching structures are to be released, means for retaining said upper latching structures in said locked position including latch bars attached to said upper shafts, chains attached to said latch bars, the weight of said chains providing means for maintaining said flattened portions substantially at right angles to said slot portions, means for locking said lower latching structures against displacement including further lower flanges attached to said wagon box having further circular openings, further slot portions merging with said further circular openings, said lower latching structures including lower shafts journalled in said lower bearings including torsion springs secured thereto and to said wagon box to provide means whereby said lower flattened portions will be substantially at right angles to said slot portions.

3. In combination with a wagon box, an end gate including latching structures at the upper corners thereof, and at the lower corners thereof, retaining members attached to said wagon box adapted to cooperate with said latching structures, means for locking said upper latching

structures against displacement while releasing said lower latching structures, and means for locking said lower latching structures against displacement when releasing said upper latching structures, said latching structures including flanges attached to said wagon box having arcuate openings therein, upper and lower bearings attached to said end gate including upper shafts journalled in said upper bearings, said openings having slot portions, said upper shafts including flattened end portions adapted to pass through said slot portions when said upper latching structures are to be released, means for retaining said upper latching structures in said locked position including latch bars attached to said upper shafts, chains attached to said latch bars, the weight of said chains providing means for maintaining said flattened portions substantially at right angles to said slot portions, means for locking said lower latching structures against displacement including further lower flanges attached to said wagon box having further circular openings, further slot portions merging with said further circular openings, said lower latching structures including lower shafts journalled in said lower bearings including torsion springs secured thereto and to said wagon box to provide means whereby said lower flattened portions will be substantially at right angles to said slot portions, means for securing said chains to said wagon box whereby said chains will act as a support for said end gate when in lowered position.

4. In combination with a wagon box, an end gate including latching structures at the upper corners thereof, and at the lower corners thereof, retaining members attached to said wagon box adapted to cooperate with said latching structures, means for locking said upper latching structures against displacement while releasing said lower latching structures, and means for locking said lower latching structures against displacement when releasing said upper latching structures, said latching structures including flanges attached to said wagon box having arcuate openings therein, upper and lower bearings attached to said end gate including upper shafts journalled in said upper bearings, said openings having slot portions, said upper shafts including flattened end portions adapted to pass through said slot portions when said upper latching structures are to be released, means for retaining said upper latching structures in said locked position including latch bars attached to said upper shafts, chains attached to said latch bars, the weight of said chains providing means for maintaining said flattened portions substantially at right angles to said slot portions, means for locking said lower latching structures against displacement including further lower flanges attached to said wagon box having further circular openings, further slot portions merging with said further circular openings, said lower latching structures including lower shafts journalled in said lower bearings including torsion springs secured thereto and to said wagon box to provide means whereby said lower flattened portions will be substantially at right angles to said slot portions, means for securing said chains to said wagon box whereby said chains will act as a support for said end gate when in lowered position, handles attached to said lower shafts for manipulating the same.

5. In combination with a wagon box, an end gate including latching structures at the upper corners thereof, and at the lower corners thereof, retaining members attached to said wagon box adapted to cooperate with said latching structures, means for locking said upper latching structures against displacement while releasing said lower latching structures, and means for locking said lower latching structures against displacement when releasing said upper latching structures, said latching structures including flanges attached to said wagon box having arcuate openings therein, upper and lower bearings attached to said end gate including upper shafts journalled in said upper bearings, said openings having slot portions, said upper shafts including flattened end portions adapted to pass through said slot portions when said upper latching

structures are to be released, means for retaining said upper latching structures in said locked position including latch bars attached to said upper shafts, chains attached to said latch bars, the weight of said chains providing means for maintaining said flattened portions substantially at right angles to said slot portions, means for locking said lower latching structures against displacement including further lower flanges attached to said wagon box having further circular openings, further slot portions merging with said further circular openings, said lower latching structures including lower shafts journalled in said lower bearings including torsion springs secured thereto and to said wagon box to provide means whereby

said lower flattened portions will be substantially at right angles to said slot portions, means for securing said chains to said wagon box whereby said chains will act as a support for said end gate when in lowered position, handles attached to said lower shafts for manipulating the same, said latch bars being positioned generally close to said upper flanges to thereby prevent lateral warping of said wagon box sides.
